J. W. OLIVER.
 ROTATABLE TOOL CARRIER FOR PLANING MACHINES, &c.
 APPLICATION FILED SEPT. 29, 1919.
1,397,014. Patented Nov. 15, 1921.

UNITED STATES PATENT OFFICE.

JOSEPH W. OLIVER, OF GRAND RAPIDS, MICHIGAN.

ROTATABLE TOOL-CARRIER FOR PLANING-MACHINES, &c.

1,397,014.

Specification of Letters Patent. Patented Nov. 15, 1921.

Application filed September 29, 1919. Serial No. 327,029.

To all whom it may concern:

Be it known that I, JOSEPH W. OLIVER, a citizen of the United States, residing at Grand Rapids, in the county of Kent and State of Michigan, have invented new and useful Improvements in Rotatable Tool-Carriers for Planing-Machines, &c., of which the following is a specification.

The present invention relates to rotatable tool-carriers for planing machines and the like, and its object is to provide a tool-carrier of that character which may be easily and economically manufactured, may be readily adapted to different service conditions and which will be particularly efficient in service.

This object is attained by the structure hereinafter described and illustrated by the accompanying drawings, in which:—

20 Figure 1 is an end view of a rotatable tool-carrier for a planing machine;

Fig. 2 is a side view of a portion of the same;

25 Fig. 3 is an end view of a blank used in making pairs of tool-clamping members of such a carrier;

Fig. 4 is an end view of such a tool-clamping member; and

Fig. 5 is an inner side view of the same.

30 In the embodiment of my invention chosen for illustration by the drawings and for detailed description in the body of this specification, the elongated body member 1 of the rotatable tool-carrier has formed at its ends means for mounting it rotatably, as the journals 2. This body member has one or more (two in the construction illustrated) table portions 3, being flat surfaces on which lie the tools, as the plane bits or irons 4, and 35 also has adjacent the opposite sides respectively of each such table portion, a first recess 5 and a second recess 6, such recesses being continuous grooves or depressions extending in the longitudinal direction of the body member as shown.

40 This body member may be made in various ways: It may be a casting, or it may be made by rolling a suitable metal bar or blank lengthwise through a rolling mill, whereby

50 the table portions and the recesses are formed by suitably shaped rollers of the mill. The table portions are "machined" or dressed down to a sufficient degree to provide a surface of flat or plane form and at a 55 proper distance from the axis of the body member to receive the tool or plane bit. The

tool-clamping members 7 are adapted to cooperate with the body member 1 of the tool-carrier to clamp the tools 4 between said members, and to that end they are provided with orifices 8 therethrough adapted to receive the shanks of bolts 9 threaded in the body member as shown. The outer portions of these orifices are enlarged at 10 to receive the heads of such bolts. These tool-clamping members 7 desirably have concave inner surfaces 11 and plane portions 12 adjacent the bolts' orifices 8, which plane surfaces disposed at the opposite ends of each concave surface portion 11 and extending in the transverse direction of the tool-carrier are adapted to contact with the tools when the same are clamped in the tool-carrier. It is desirable that the tool-clamping member 7 shall clampingly engage the tool near its cutting edge (i. e. adjacent the first recess 5) more tightly than said tool is thus engaged farther back from its cutting edge, as toward the clamping bolts 9. To effect this end, the tool-clamping members are provided with rearward portions 13 adapted to abut against that side 14 of the second recess 6, which side is remote from the tool: the inner surface of the tool-clamping members at 15 engaging the tools near their cutting edge 85 and the rearward abutting portions 13 of the tool-clamping members engaging the sides 14 of the second recesses 6 tightly under the action of the bolts, before such bolts (located between said tightly engaging portions of the tool-clamping members) are turned sufficiently to press or spring the plane surfaces 12 of said members into close engagement with the tools more rearwardly from their cutting edges. To provide for a proper formation of the rearward portion of the tool-clamping member, the edge of its said portion 13 (as such member is first formed) desirably extends farther than necessary to accomplish the end above described and is 90 thereafter cut or dressed down sufficiently to enable the members 1 and 7 to securely clamp the tool between them in the manner described.

95 This tool-clamping member 7 may be made in various ways: It may be a casting, or a drop forging; desirably such members are to be made in pairs by forming an elongated blank 20 (seen in Fig. 3) substantially circular in cross-section and with a longitudinally disposed wide groove 21 extending inwardly beyond the axis of the blank. The

blank may then be severed longitudinally midway between the sides 22, 23 of said groove, as on the line 24 in said figure. Such severing provides a pair of tool-clamping members, whose rearward abutting edges may be cut down as hereinbefore explained, as along the dotted lines 25, in Fig. 3.

The two members 1 and 7 of the tool-carrier being provided, they may be bolted together by the bolts 9, with a suitable filler piece (not shown) between them, such filler piece being somewhat thicker than the tool to be used in the tool-carrier. In such bolted-together condition the edge of the rearward portion 13 of the tool-clamping member 7 abuts against the side 14 of the recess 6. The periphery of the entire tool-carrier is now cut or turned down in a lathe to the desired diameter, such periphery when such turning operation is finished being shown at 26 in Fig. 1. It will be seen that inasmuch as the filler piece is somewhat thicker than the tool to be used in the tool-carrier, the tool-clamping member will more tightly clamp the tool near its cutting edge than rearwardly therefrom when the tool is held between the members 1 and 7. The body member 1 may be formed in initial or rough form to extend beyond its finished periphery 26, such extensions being shown in dotted lines at 27 in Fig. 1. Dotted arcuate lines 28 in said figure illustrate the degrees to which the body member may be turned or dressed down to provide a tool-carrier of desired diameter; and dotted arcuate lines 29 in Fig. 3 illustrate degrees to which the tool-clamping member may be dressed or turned down for the same purpose. The dotted lines 30 in Fig. 1 illustrate position

of the surface of the table portions 3 to 40 which such portions may be cut or dressed to accommodate tools of greater thickness.

Suitable openings 40 are provided through which a tool may be thrust to adjust the position of the plane bits.

The processes or methods whereby the above described structure may be manufactured are made the subject of my divisional or separate application Serial Number 456,155 filed March 28th, 1921.

The invention being intended to be pointed out in the claim, is not to be limited to or by details of the construction of the particular embodiment of the invention, hereinbefore set forth or illustrated, further than the same is or are specified in the claim.

I claim:

A rotatable tool-carrier for a machine of the character described, comprising; an elongated body member having means at its ends for mounting the same rotatably, and having a table portion, and first and second recesses adjacent opposite sides respectively of the table portion; a tool-clamping member coöperating with the table portion to clamp the tool therebetween, and having a concave inner surface, orifices to admit clamping means, and plane inner surfaces adjacent said orifices disposed at the opposite ends of said concave inner surface and extending in the transverse direction of the tool-carrier; clamping means extending through said orifices for clamping said members together with the tool between them.

In testimony whereof I have hereunto set my hand at Grand Rapids, Michigan, this 26th day of September, 1919.

JOSEPH W. OLIVER.
